Primary Examiner—Susan Moon Lee*(74) Attorney, Agent, or Firm*—Jackson Walker, LLP(57) **CLAIM**

I claim the ornamental design for a wildlife feeder, as shown and described.

DESCRIPTION

FIG. 1 is a front perspective view of a wildlife feeder showing my new design;

FIG. 2 is a front elevational view thereof.

FIG. 3 is a top elevational view thereof.

FIG. 4 is a left side elevation view thereof.

FIG. 5 is a rear elevational view thereof.

FIG. 6 is a right side elevational view thereof; and,

FIG. 7 is a bottom elevational view thereof.

Any portions comprised of broken line are not claimed.
